DESIGN FOR A HAT

Aaron M. Hartman, New York, N. Y.

Application January 29, 1940, Serial No. 89,839

Term of patent 3½ years

To all whom it may concern:

Be it known that I, Aaron M. Hartman, a citizen of the United States and residing in the city, county, and State of New York, have invented a new, original, and ornamental Design for a Hat, of which the following is a specification, reference being had to the accompanying drawing, forming a part thereof in which:

Fig. 1 is a front elevational view of the hat showing my design.

Fig. 2 is a side view of Fig. 1, and
Fig. 3 is a rear view of Fig. 1.

The characteristic feature of the invention resides in the hat band of the configuration, and arrangement as shown in the full lines on the drawing.

I claim:

The ornamental design for a hat, substantially as shown and described.

AARON M. HARTMAN.
